JOHN E. GREENAWALT, OF DENVER, COLORADO.

APPARATUS FOR ROASTING AND SINTERING ORES.

1,088,818.

Specification of Letters Patent.

Patented Mar. 3, 1914.

Original application filed March 24, 1913, Serial No. 756,519. Divided and this application filed September 26, 1913. Serial No. 791,976.

To all whom it may concern:

Be it known that I, JOHN E. GREENAWALT, citizen of the United States, residing at Denver, in the county of Denver and State 5 of Colorado, have invented certain new and useful Improvements in Apparatus for Roasting and Sintering Ores, of which the following is a full, clear, and exact description, reference being had to the accompanying drawings, forming a part hereof.

My invention has relation to improvements in apparatus for roasting, sintering, and otherwise treating ores and other material; and it consists in the novel features 15 of construction more fully set forth in the specification and pointed out in the claims.

In the drawings, Figure 1 is a side elevation of an ore-sintering pan surmounted by an ignition hood, showing the application 20 of my invention thereto, parts being broken away; Fig. 2 is a vertical cross-section on the line 2—2 of Fig. 1; Fig. 3 is a part elevation and part vertical middle section of a burner employed in connection 25 with, and forming a component part of, my apparatus; Fig. 4 is a horizontal section on the line 4—4 of Fig. 3; Fig. 5 is a horizontal section on the line 5—5 of Fig. 3, parts being broken away; Fig. 6 is a detached plan view of the slotted disk 30 through which the burner fluid is sprayed; Fig. 7 is an edge view of Fig. 6; and Fig. 8 is a plan of a disk having a series of slots of unequal widths.

The present is a division of the subject-matter of my original application for patent for improvements in oil burners, filed March 24, 1913, Serial Number 756,519, which matured into Patent Numbered

43 1,084,939, dated January 20, 1914, the subject-matter hereof being directed to apparatus for roasting and sintering ores (or treating other material) *en masse*, where it becomes important to simultaneously ignite 45 the entire surface of the charge in order to insure an even and uniform propagation therethrough of the zone of combustion. This simultaneous ignition of an extended surface of the charge depends for its success not only upon the intensity and direction of projection of the igniting fuel over such surface, but upon the position, of the point or points from which the fuel is projected, relative to the outer boundaries of 50 the charge, especially in processes where the

charge is subjected to the action of a down-draft current of air to supply the necessary oxygen to the combustible components of the charge. Instances of such downdraft for purposes of roasting, oxidizing, sintering and otherwise treating ores are to be found in my U. S. Patents 839,064 and 839,065, dated December 18, 1906, and in my pending application for sintering apparatus, filed June 24, 1912, Serial Number 705,495. Where, as in the latter example, a charge is sintered *en masse*, provision must be made to effect a simultaneous ignition of the entire surface of said charge; and to accomplish this effectively, burners 60 must be employed which will not only project the igniting fuel across the charge in paths substantially parallel to its surface, but with sufficient intensity or under sufficient head, to prevent material deflection of 65 the projected streams, by the transverse currents of air traversing the body of the charge from top downward, such traverse as well understood, being due to the action of the exhaust producing the downdraft 70 (or its equivalent). If the projected streams of igniting fuel or inflammable material were deflected by the downdraft (or transverse current) to any material extent, a considerable proportion thereof would be 75 sucked or drawn (or forced where pressure apparatus were used in lieu of an exhaust) into the body of the charge before said inflammable material or igniting fuel could be ignited above the charge, the portion 80 thus prematurely drafted (or otherwise diverted) into the charge being lost and rendered unavailable for the purpose for which it was intended.

It is therefore one of the objects of my 85 present invention to provide an ore-roasting or sintering apparatus of the general character alluded to, in which provision is made to introduce the igniting fuel above the charge from points within the outer 90 boundaries of the charge, said fuel being projected preferably in the shape of inflammable material (gaseous, liquid or solid) from points above and within the boundaries of the surface of the charge, toward 95 said boundaries (that is to say outwardly) in paths substantially parallel to the surface of the charge and under a head sufficient to overcome any material deflection 100 thereof by the transverse currents traversing 105 the charge.

ing the charge from top downward (or at right angles to the paths of projection of the igniting fuel).

A further object of the invention is to provide means which will project the streams of igniting fuel radially over a wide area, said area being disposed in a plane directly over, and substantially parallel to, the surface of the charge of ore (or other material) to be treated. Air under pressure is preferably employed as the impelling agent by which the projection of the igniting fuel is effected, although any equivalent gas may be substituted for air. The streams of igniting fuel may be projected from any suitable member or burner-head having passages so disposed as to cause the streams to follow paths substantially parallel to the surface of the charge, but I have found in practice that a burner the details of which I shall presently describe is eminently adapted for the purpose here in view. I do not however, wish to be understood that the burner here illustrated and described is the only one available for use in connection with my invention, as it is quite obvious that any burner or device operating in a manner substantially equivalent thereto is contemplated by my invention. Inasmuch as the burner (or its equivalent) forms an element of the combination relied on to bring about the results contemplated by the invention, the details of one form of burner will be described in connection with the ore holder or furnace with which it is associated.

The invention in detail including a description of the burner, may be described as follows:—Referring to the drawings, and for the present to Figs. 1 to 7 inclusive, 1 represents a pan or treatment receptacle which in practice may be of any convenient size, the dimensions of that here shown being about twelve feet in length, seven feet wide, and two feet deep, the same being provided with grates G or equivalent perforated support for the charge m, the thickness of the charge being about twelve inches, and the upper surface thereof disposed substantially flush with the edges of the pan. The grates are raised above the bottom of the pan so as to leave a vacuum chamber 4 between the grates and said bottom, the pan being provided with hollow trunnions 5 (about which it is rotatable) communicating respectively with said chamber 4 and through casings R and pipes P, P, with a suitable exhauster E. Adapted to be deposited on the pan directly over the charge is a hood H the roof of which (provided as in my pending application with air intake openings o, o') is sufficiently raised above the surface of the charge to form a combustion, roasting and igniting chamber 6 above the charge, the parts thus far de-

scribed being in all essential particulars the same as in my pending application aforesaid, and being herein necessarily referred to in order to show their relation to the burner forming one of the elements of the present invention.

In the present application of my invention I employ two burners B, B, mounted on the roof of the hood and discharging into the chamber 6, there being one burner 75 on each side of the transverse axis of the hood, and removed equal distances from said axis, each burner thus covering or igniting an area six by seven feet, of the total area of twelve by seven feet of the ore 80 charge. Mounted above the hood and supported thereby in any mechanical manner is an oil tank T, from the bottom of which leads a discharge T 7 communicating with an oil line 8 disposed parallel to the length 85 of the tank and extending in opposite directions from said T 7, each branch of said line being provided with a suitable control valve V beyond which is located a standard Schutte-Koerting strainer 9, the branches 90 of the oil line discharging into the burner, through the top thereof. Tapping the oil tank at the top and communicating with the air space above the oil in the tank is a compressed-air supply pipe 11 provided with an 95 air-valve 12, said pipe connecting to a suitable flexible hose 13 which leads to any suitable source of compressed air supply (not shown). The compressed air or other gas in the tank T above the surface of the oil 100 discharges through a reducing valve, pop valve, or equivalent pressure-regulator 15, into an air-line 16, the said line running in opposite directions from the valve 15, each branch discharging tangentially into its respective burner, the air-branches being likewise provided with a standard make of strainer 9'. The novelty of the foregoing features resides of course in the relation of the several parts to one another, and not in 110 the specific construction of any one element.

Directing our attention to the construction of the burner *per se*, and to its specific disposition within the igniting chamber 6, the said burner is composed of two sections 115 a, b, the former being hollow or tubular and substantially cylindrical in form, the sections being united to one another by means of bolts 17 passed through the section b and through the basal enlargement a' 120 of the section a. Between the sections there is interposed a sheet metal plate or disk 18 or equivalent spacing member, the said disk resting on the inner face of the section b and being provided with a series of radial slots s open at the outer ends, the inner closed ends terminating within the chamber C of the burner as shown, the disk having a central circular imperforate section h from the periphery of which the slots 130

radiate. The slots thus form radial channels with the opposing faces of the sections *a*, *b*, for the escape of the oil from the chamber of the burner into the atmosphere. The portion *h* of the disk serves as a support for the central spreader or cone 19 which is secured to the disk and to the section *b* of the burner by a screw-bolt 20 or equivalent mechanical manner. The cone serves not only to hold the disk 18 firmly against the bottom section *b*, but it likewise serves to distribute, and direct the oil into, the several channels aforesaid. The base of the cone 19 comes inside the closed terminals of the slots or channels *s*, whereby free communication is afforded through the channels between the atmosphere and the chamber C (termed for convenience as the mixing-chamber). The disk 18 is provided with 20 holes O for the accommodation of the bolts 17.

As seen from the drawings, the plane of separation between the burner sections *a*, *b*, is at right angles or transverse to, the axis 25 of the mixing chamber, so that the paths of discharge of the oil and gases from the burner are in the corresponding plane, any oil not fully atomized being caught in the gutter 21 formed around the periphery of the 30 burner-section *b*. The upper end of the burner-section *a* is provided with a hollow screw-plug 22 to which are respectively secured the discharge end of the oil-line branch 8 (the connection being made by 35 an elbow 23 passed over the end of said branch and over a pipe 23' inserted into the plug), and a standard spray-nozzle 24, the latter being preferably of the Schutte-Koerting variety well known in the art. The axis 40 of the spray-nozzle is coincident with the axis of the burner as shown, whereby the spray of oil is symmetrical about said axis. The air line 16 communicates with the mixing chamber at the top thereof, the air being introduced preferably at a tangent to 45 the inner wall of the chamber whereby a whirling movement is imparted to the air within the chamber. The connection is made at the opening 25 in the boss 26 of the wall 50 of the section *a*. The spray-nozzle 24 requires at least fifteen pounds pressure to spray the oil into the free atmosphere at normal temperatures, and some heavier oils require even more. The oil however, is 55 sprayed into the chamber C which itself is under a pressure approximating forty pounds, so that the pressure required to force the oil into the chamber, other things being equal, will be fifteen plus forty pounds 60 or approximately fifty-five pounds. The slots *s* though shown in the figures aforesaid as being of uniform size, may have one or more of them as *s'* enlarged over the other as shown in the modification in Fig. 8, such enlargement allowing a greater vol-

ume of air to pass through, and hence projecting further the flame at such points.

In the specific application of the burner as here shown, its success depends on the accuracy and perfection with which the oil is subdivided and delivered to the radial slots or channels *s*. In other words, it is important that each slot or channel shall receive exactly the same amount of oil. This accurate subdivision follows to a considerable degree from the use of the spreader or cone 19, which as heretofore stated directs the distribution of the oil into its proper channels. The said subdivision likewise depends for its full realization on the use of the spray nozzle within the mixing chamber C whereby the oil is fully atomized or subdivided before it is delivered to the channels *s* (of which there should always be a plurality) through which the oil is delivered in 85 radial sprays or jets by the blast of air or other gas entering said chamber under pressure from the oil tank. The degree of pressure availed of to project the oil through and out of the 90 channels depends on the area it is desired to cover with the flame; the greater the area the greater the pressure necessary to project the oil or resulting flame. The air being under pressure flows through the slots or 95 channels in proportion to the cross-sectional area of the slot, the volumes of air passing through the slots being equal if the cross-sectional areas of the slots are equal, the projected streams being substantially 100 of equal length. It will be seen that the streams of sprayed and atomized oil projected from the channels *s* being disposed in substantially the same plane, will collectively form an inflammable sheet of atomized fuel which when ignited will form a sheet or blanket of flame, said blanket (if sufficient driving pressure be behind it) being coextensive with the surface of the charge and serving 105 to simultaneously ignite the entire surface of said charge. To render this possible, it is of course obvious that the intensity of projection of the streams must be such as not to suffer any material deflection from 110 their substantial parallelism with the surface of the charge (to be ignited) by the transverse air currents traversing the charge from top downward, in response to the action of the exhauster; otherwise some of the 115 inflammable material or oil-spray would be drawn prematurely into the body of the charge and there lost, not having a chance to form into flame before suffering the deflection referred to.

The operation of the burner employed in the connection here described may be stated as follows:—Air under sixty (60) pounds pressure or more is delivered to the oil tank T into the space above the oil whereby 130

oil is delivered at said pressure to the spray-nozzle 24, the said nozzle subdividing and spraying the oil into the mixing chamber. This subdivision of the oil permits each 5 channel or slot s to receive its proper proportion of oil so that the resulting flame is one of uniform intensity and spreads over an extended area (each burner in fact discharging a flame coextensive with one-half 10 the surface of the charge in the pan 1). The air as it passes from the tank flows through the reducing valve 15 which reduces the pressure say about eighteen pounds, thus allowing the air blast which enters (tangentially) 15 the chamber of the burner to flow into said chamber at about a pressure of forty-two pounds (more or less), the consequent intimate mixture of sprayed oil and air passing into the channels s (at a pressure 20 which will depend on the relation between the combined areas of the channels s , and the area of the opening 25), the oil being again atomized and sprayed as it discharges from the channels. The sprays being delivered 25 substantially at right angles to the axis of the burner, and said axis being perpendicular to the (horizontal) surface of the charge m , it follows that the series of radial sprays thus projected from each burner will 30 collectively form a sheet of inflammable particles which when ignited will result in a sheet of flame or in a burning blanket which in turn effectively and almost instantaneously (and before the inflammable particles 35 can be prematurely deflected into the charge by the exhauster) ignites simultaneously the entire surface of the section of the charge which is beneath said blanket, each burner thus igniting one-half of the surface of the 40 ore charge, and both burners igniting the entire surface of such charge. Inasmuch as both burners work simultaneously, it follows that both sections of the surface of the charge will be ignited at one and the same 45 time, so that the zone of combustion of the combustible components of the charge will propagate itself evenly and uniformly through the charge from top downward in the general direction of the transverse air currents drafted through the charge by the 50 action of the exhauster. The burner here shown operates on a minimum amount of liquid compared with the size and intensity of the sheet-flame produced, and may be 55 used in many arts not necessarily akin to roasting or sintering ores.

The pressure "differential" or excess of eighteen pounds pressure here alluded to under which the oil is driven into the chamber of the burner member against the pressure of air or gas maintained within said chamber for expelling the liquid, may of course vary. This differential will depend in a measure on the kind of spray-nozzle 60 used, on the radius of projection of the

streams desired through the slots (or equivalent vents), the cross-sectional areas of the slots, and on a variety of circumstances. The proper differential however, can always be determined by the operator according to 70 the work to be performed. The driving pressure of the liquid should of course be in excess of the gas pressure maintained in the mixing chamber so as to insure the projection of the liquid into the chamber. It may be added that in lieu of liquid fuel any fluent material gaseous or solid, may be substituted.

In the practice of my invention as described, the oil sprayed from the burners may be ignited either as the hood is being deposited over the pan, or it may be ignited after the pan is deposited, by a torch inserted through a torch-hole (not shown) placed where convenient, according to the 80 wish of the operator. It may be stated in passing that by providing a spray-disk (such as 18, Fig. 8) with slots s , s' , of various widths (or unequal dimensions) I can vary the distance of projection through the different slots, and hence vary (to suit my purpose) the areal configuration or shape of the resulting sheet of inflammable material formed by the sum total of all the sprays discharged from the disk. For example, by providing the disk with radial slots of equal dimensions there results substantially a circular sheet of sprayed material; by varying the dimensions of some of the slots I could secure a square or polygonal sheet, so that any areal configuration of sheet is possible.

As in my pending application aforesaid, the hood H when deposited on the pan 1 makes a chamber 6 therewith above the charge, said chamber being sealed (at the sides and ends) by reason of the tight joint made between the machined surfaces of the edges of the hood and pan respectively when said hood is deposited on the pan. In the present invention however, the streams of igniting fuel or inflammable material are directed outwardly toward the seal between the hood and pan, instead of inwardly from points along the walls of the hood. This new arrangement has the advantages, (1) that by locating the spray-device or burner in the chamber 6 at a point within the outer boundaries of the charge, the projected streams have a less distance to travel to 105 cover the area of the charge, thus insuring more positive and satisfactory results; and (2) in the event that the contacting surfaces between the hood and pan are not clean to insure a tight joint or seal when the hood is deposited on the pan preparatory to the ignition of the charge, any air which would tend to leak into the roasting chamber 6 through the imperfect joint or seal would be arrested or checked by the 110 115 120 125

streams of inflammable material projected outwardly or toward and against the seal from the burner or equivalent spray device thus located within the chamber. The arrest and checking of any currents leaking through an imperfect seal is desirable as they tend to disturb, and interfere with the integrity of the zone of combustion, as pointed out in my pending application 5 aforesaid. Generically therefore, the present improvement contemplates the projection of streams of inflammable material from a point or points within the roasting chamber, outwardly toward the boundaries 10 of the charge treated, in planes substantially parallel to the surface of the charge; and where the charge is supported in a treatment vessel covered by a hood, the invention contemplates specifically the projection of the 15 streams from a point within the chamber toward the seal or joint between said vessel and hood, it being understood of course, that the projection of the streams is under sufficient head so as not to suffer material deflection by the transverse currents traversing 20 the charge.

Features shown but not alluded to are old in the art, or are already embodied in my pending application aforesaid, and a 25 description of the same is here unnecessary, especially as they form no part of the present invention.

Having described my invention, what I claim is:—

35 1. In combination with a treatment vessel containing a charge, and provided with a chamber above the charge, means positioned in the chamber above the charge at a point within the outer boundaries of the surface 40 of the charge, and operating to project inflammable material over said surface toward the boundaries thereof aforesaid.

2. In combination with a treatment vessel containing a charge, and provided with a 45 chamber above the charge, means positioned in the chamber above the charge at a point within the outer boundaries of the surface of the charge, and operating to project inflammable material toward said boundaries, 50 and means for directing the inflammable material so projected, in paths substantially parallel to the surface of the charge.

3. In combination with a treatment vessel

containing a charge, a hood adapted to be deposited thereover and forming a chamber 55 above the charge, and means carried by the hood at a point above the charge and within the boundaries of the surface thereof, and operating to project into said chamber inflammable particles in paths substantially 60 parallel to said surface.

4. In combination with a treatment vessel having a perforated support for the charge, a hood adapted to engage said vessel and form therewith a sealed chamber above the 65 charge when so engaged, an exhauste coupled to the vessel, and means in the chamber positioned above the charge within the outer boundaries of the charge, and operating to project inflammable material into 70 the chamber in paths substantially parallel to the surface of said charge, and direct said material toward the seal aforesaid and toward the aforesaid boundaries of the charge.

5. In combination with a treatment vessel 75 having a perforated support for the charge, a hood adapted to engage said vessel and form therewith a sealed chamber above the charge when so engaged, an exhauste coupled to the vessel, means in the chamber 80 positioned above an intermediate point of the surface of the charge and operating to project radially outward, inflammable particles toward said seal in paths substantially parallel to the surface of the charge, and 85 means for introducing a supporter of combustion through the hood into the sealed chamber.

6. In combination with a treatment vessel having a perforated support for the charge, 90 a member coöperating with said vessel and forming therewith a chamber above the charge, an exhauste coupled to the vessel, and means in the chamber positioned above the charge within the boundaries of the 95 charge, and operating to project inflammable material into the chamber toward said boundaries, in paths substantially parallel to the surface of the charge.

In testimony whereof I affix my signature 100 in presence of two witnesses.

JOHN E. GREENAWALT.
